UNITED STATES PATENT OFFICE.

LOUIS LIPAWSKY, OF NEW YORK, N. Y.

HAT-PIN PROTECTOR.

1,163,833.

Specification of Letters Patent. Patented Dec. 14, 1915.

Application filed July 20, 1914. Serial No. 852,111.

To all whom it may concern:

Be it known that I, LOUIS LIPAWSKY, a subject of the Czar of Russia, residing at New York, in the county of New York and State of New York, have invented certain new and useful Improvements in Hat-Pin Protectors, of which the following is a specification.

This invention relates to means for securing ladies' hats upon the head, and more particularly to that class which employ a pin that is very long and is stuck through the crown of the hat into the hair and out of the opposite side of the crown from that of its entrance.

One of the objects of this invention is the production of a device to be used in combination with such a hat-securing means as above described that will obviate the marking of the hat by numerous holes made by the placing of the pin therethrough.

Another object of this invention is to provide a hat pin securing device that will accomplish the two fold purpose of preventing the accidental removal of the hat pin from the hat and to guard the protruding end of the hat pin from coming in contact with persons and injuring them.

A still further object of this invention is the provision of a positive gripping means for the pin and also provides means whereby the grip can be easily released from the pin and the same withdrawn from the hat.

A still further object of this invention is the production of a device as above described that is simple in construction, efficient in operation and consists of the minimum number of parts.

With these and other objects in view this invention consists of certain novel constructions, combinations and arrangement of parts as will be hereinafter described and claimed.

In the accompanying drawings:—Figure 1 is a sectional view of a hat with the improved device mounted thereon. Fig. 2 is a sectional view taken on the line 2—2 of Fig. 1. Fig. 3 is a view in elevation of the securing disk used with this device. Fig. 4 is a view in elevation of a pin guiding means used with this invention. Fig. 5 is a side elevation of one end of the housing for the gripping means.

Referring to the parts by reference numerals, a hat is indicated by 10 having openings 11 and 12 therethrough. A cir-

cular plate 13 having an opening 14 formed centrally therethrough, and extending from the sides of the opening is an externally threaded collar 14. This circular plate 13 is placed adjacent the opening 11 formed in the hat and the collar or projection 14 is passed through said opening 11, and on the portion of the collar or projection 14 that projects beyond the edge of the opening 11 is threaded a plate 15 which is of the same size as the plate 13. Apertures 16 are formed in the two plates 13 and 15, and are adapted to be placed in alinement so as to receive thread or other means passed through the hat to securely fasten the same upon the hat if so desired.

On the inner face of the crown of the hat 10 is a disk 17 having an opening formed centrally thereof, and extending from the edge of said opening is an externally threaded projection or collar 18. This collar or projection 18 is positioned through the opening 12 formed in the hat.

A housing 21 is provided with gripping means for the hat pin, and said housing is positioned adjacent the opening 12 formed in the hat, which is the larger of the two openings formed in the same, said housing 21 having at one end a disk 19 having a threaded opening positioned centrally thereof, said threaded opening being threaded upon the projection 18 formed on the disk 17. Thus the housing 21 is substantially held to the hat by means of its engagement with the projection or collar 18 formed on the disk 17. If it is wished to further secure the housing to the hat, there is provided in the disk 19 formed at one end of the housing and in the disk 17 perforations 20, through which, when the same are in alinement, thread or other fastening means may be passed.

To facilitate the gripping of a pin that is projected through the opening 12 and into the housing, are provided a pair of gripping members 24, that comprise inwardly bent gripping ends 25 and at the opposite end of the same outwardly flared finger engaging portions 26. Intermediate the length of the gripping members 24 are alined apertures that receive the securing means, such as a small bolt or rivet, indicated by the numeral 27. Said securing means have mounted thereon a coil spring 28 that engages the inner faces of the gripping members against the openings through which the securing

means pass. As is clearly shown in Fig. 1, the housing 21 has its end through which the bolt or pin 27 passes reduced; the gripping members 24 are of such shape as to conform to the contour of the inner face of the reduced end of the housing 21, so that when the finger gripping portions 26 are engaged and move toward one another, the intermediate portion of the gripping members 24 will be rocked on the housing and thus move the gripping portions 25 away from one another. This means for retaining a hat pin in a hat could be used with any conventional form of a hat pin, but I have shown a hat pin 29 having a head 30 at one end thereof, and adjacent the point end of the pin is formed an annular groove 31. This groove is adapted to be engaged by the gripping portions 25 of the gripping members, and thereby insures the positive retaining of the pin in the housing.

When it is wished to secure a hat provided with the improved means described, all that is necessary is to project the hat pin through the opening 11, and of course, the protector for the opening, namely, the plate 13 and through the opening 12, inasmuch as the hat pin's pointed end is tapered, the same will open the gripping members and the tension of the springs will hold the gripping members thereon. It will be seen that the gripping portions 25 of the gripping members are bent slightly away from the direction of the pin when the same is being inserted, so as said pin can be guided to the ends of the gripping members and by

the pointed end of the same open them without applying the fingers to the outwardly flared portions 26.

A means has been provided that obviates the marring of the hat by numerous holes that are caused by the insertion of the pins at different places on the hat, and a positive retaining means for a hat pin is also provided. Furthermore, there is absolutely no likelihood of the projecting end of the pin engaging an object or person, inasmuch as the same is entirely covered.

It is obvious that minor changes may be made in the form and construction of this invention, and it is not wished to confine the device as disclosed, but to include all such as properly come within the scope of the appended claim.

I claim—

A hat pin protector comprising a housing adapted to be secured to a hat, one end of said housing reduced and the inner wall thereof presenting a substantially curved face, and a pair of gripping members pivoted in said housing, said members each curved to conform to the contour of the inner wall of the reduced portion of said housing to facilitate the movement of said gripping members in said housing.

In testimony whereof I affix my signature in presence of two witnesses.

LOUIS LIPAWSKY.
